[57] CLAIM

The ornamental design for an injector for introducing contrast agents into blood vessels, as shown.

DESCRIPTION

FIG. 1 is a perspective view of an injector for introducing contrast agents into blood vessels, showing my new design;

FIG. 2 is a rear end elevational view thereof;

FIG. 3 is a front end elevational view thereof;

FIG. 4 is a top plan view thereof, the bottom view being identical thereto;

FIG. 5 is a side elevational view thereof, the opposite side being identical thereto.

FIG. - 1**FIG. - 2****FIG. - 3**

FIG. — 4**FIG. — 5**
